[57] CLAIM

The ornamental design for a binder with display pockets, as shown.

DESCRIPTION

FIG. 1 is a perspective view of a binder with display pockets showing the front cover thereof, with cards being shown in phantom for illustrative purposes only and forming no part of the claimed design;

FIG. 2 is a front elevational view thereof, with cards being shown in phantom for illustrative purposes only and forming no part of the claimed design;

FIG. 3 is a rear elevational view thereof;

FIG. 4 is a left side elevational view thereof;

FIG. 5 is a right side elevational view thereof;

FIG. 6 is a bottom plan view thereof; and,

The photograph on the lower front right corner of the article is shown partially removed from its pocket for clarity of illustration only.

FIG. 7 is a top plan view.
